COMBINED ARC LAMP AND INCANDESCENT LAMP

Harold J. Brunk, Chicago, Ill., assignor to The C. F. Pease Company, a corporation of Delaware

Application May 21, 1937, Serial No. 144,090

1 Claim. (Cl. 176—9)

This invention relates to improvements in combined arc lamps and incandescent lamps, and while such equipment is adapted for many purposes it is particularly useful as a source of light in blue print machines and the like.

The main object of this invention is to provide equipment converting a much larger proportion of the energy into usable light than has heretofore been possible with arc lamps.

10 The solenoid type of operating mechanism is preferred in arc lamps of the automatic type, wherein the separation of the carbons from each other is properly adjusted by the pull of the solenoid, which is in turn a function of the current flow across the carbons. When the carbons are separated too far, the resistance of the arc gap increases, the current flow across the gap decreases, and thus the solenoid pull is lessened and permits the carbons to move relatively closer together until the increasing current flow stops such movement.

For many reasons it has been found undesirable to pass more than eight or ten amperes through the solenoid of the average lamp of this type, and 25 in order to increase the amount of light radiated by the arc it is necessary to pass current through the carbons by some second or additional circuit which does not include the solenoid. My joint Patent 1,992,650, issued February 26, 1935, shows 30 a method of increasing the current through the carbons without changing the current through the solenoid, by establishing a second or shunt circuit around the solenoid after the carbons have separated and assumed proper operating position.

35 This enables the current density across the gap, and thus the light intensity, to be varied through a wide range, while the arc lamp maintains great stability.

Such a secondary circuit, however, must absorb 40 a voltage drop equal to that across the solenoid. That is, should the carbons and the solenoid be in series across a 220 volt supply line, either A. C. or D. C., and each have a 110 volt drop thereacross, it is necessary that the second or shunt 45 circuit include a ballast resistance of some type substantially equivalent to the arc gap resistance in order to absorb the extra 110 volt drop when it is placed in series with the carbons across the supply line. It is always necessary to use also a 50 ballast resistance in series with the solenoid in order to achieve arc stability.

It has heretofore been customary to use impedances of one type or another for such ballast purposes, as shown in my prior patent. Such 55 ballast resistances absorb power without giving off

light, which latter is the desired output in the case of a lamp.

The present invention comprises means for greatly increasing the light output of such devices; first, by providing a shunt path permitting 5 a higher current concentration through the carbons without upsetting the adjustment of the solenoid; and second, by replacing ballast resistances in the device by additional light sources or lamps having an equivalent resistance, the auxiliary 10 lamps not being rendered operative until the carbons have assumed proper operating separation.

Other features and advantages of this invention will be apparent from the following specification and the drawings, in which:

Figure 1 is a side elevation of a solenoid-operated arc lamp; Figure 2 is a circuit diagram of such a lamp; Figure 3 is a circuit diagram of a lamp wherein all ballast resistances are replaced by auxiliary lamps when the carbons have 20 reached proper operating separation; Figure 4 is a diagram of a circuit enabling ready adjustment of the amount of current flow across the carbons; and Figure 5 is a diagram illustrating the alternate arrangement of lamps.

In the particular embodiment of the invention illustrated in Figs. 1 and 2, a pair of carbons 10 and 11, movable with respect to each other, are operatively carried in a lamp having a globe 12 and a reflector 13. The upper carbon 10 is 30 here shown as movable, its separation from the other carbon being determined by the position of the movable rocker arm 14, movement of this arm being effected through appropriate linkage by movement of the core or plunger 15 as a result 35 of current flowing in the solenoid 16. A dashpot 17 is provided to prevent sudden movement of the carbons and stabilize the lamp.

The rocker arm is here shown as carrying a mercury switch 18. Reference more particularly 40 to Figure 2 will show that this mercury switch is connected in circuit between the carbons and an incandescent lamp 19. The solenoid 16 has in series therewith an adjustable resistance 20. Thus, two current paths are provided through 45 the carbons: one, a series circuit including the carbons, the solenoid, and the resistance 20; and the other a second series circuit including the carbons, the mercury switch 18, and the incandescent lamp 19. It will be noted that the incandescent lamp is in shunt across the solenoid and the resistance 20, so that current flowing through it flows directly through the carbons without any effect on the solenoid.

The mercury switch is so arranged that when 55

the carbons are in contact with each other, the circuit therethrough is broken, and the only current flow is through the solenoid and the resistance 20. Movement of the rocker arm 14, as 5 the carbons separate, causes the mercury switch to tilt, however, and the apparatus is so constructed and arranged that when the carbons have reached proper operating separation the mercury switch closes the circuit through the incandescent 10 lamp, thus materially increasing the flow of current through the carbons due to the provision of two circuits, and thus increasing also the amount of light given off thereby. Not only does this 15 additional current result in a much higher proportion of light being given off by the carbons, but the total light is increased by that given off by the filament of the second or auxiliary lamp 19, which is mounted adjacent the arc lamp.

In many uses of the arc lamp, as for example by 20 photoengravers, the amount of work done depends on the total candle power of the light source, and it is obvious that when one or more thousand watt incandescent lamps, burning at full brilliancy, are added to the arc as a light source, 25 the total foot candles of the device are greatly increased. While the light from a gas-filled tungsten lamp is not of the best frequency to make blueprints, the addition of the light has a marked value even in such work. The incandescent lamps used to replace the resistances in such blueprinting lamps should be maintained in the blueprinting machine between the arc lamps, where they will help to build up the weak printing area otherwise encountered therebetween. An additional factor is that with a 30 fairly heavy current flowing through the arc, there is a greater production of actinic rays which are found at that end of the spectrum which is the most effective in photographic work. For other uses, the incandescent lamps can be 35 mounted in a special compartment around the outside of the standard arc lamp reflectors. Where general illumination is required in a room where such arc lamps are employed, the ceiling or other lamps can be wired in, to act as resistors 40 in connection with the carbons, thus achieving the greatest possible amount of light energy from current being consumed.

It will be readily apparent that any type of lamp 45 having a resistance drop therein could be used for the secondary or auxiliary lamps. Not only the usual gas-filled tungsten filament lamp, common on the market today, but also high pressure mercury arc or any other types of lamps are adapted to be used in series with the electric arc 50 as here disclosed. The principal purpose is to have all of the current used go toward making light, rather than being dissipated in undesired heat energy, one portion of the current developing light in the arc across the carbons, and the 55 other portion developing additional light, which may or may not be of the same wave length as that of the arc, in the secondary or auxiliary lamps.

60 Referring more particularly to Figure 3, a circuit is shown wherein two auxiliary lamps are employed. The lamp 31 may be of considerable power, such as one thousand watts, and is connected in series with the carbons 32 and 33 through a mercury switch 34. As described in 65 connection with Figure 2, this mercury switch closes the circuit when the carbons 32 and 33 have separated to proper operating distance. In addition, a smaller lamp 35, as of 600 watts, is provided 70 to replace the resistance 36 in series with the sole-

noid 37 when the arc has been properly drawn. In order to accomplish this, a second mercury switch 37 is also mounted so as to be tilted by some moving part actuated by the solenoid, and as in the case of the other mercury switch, it may be 5 mounted on the rocker arm of the device. This second switch is so arranged that when the carbons are in contact, the circuit through the wires 38 and 39 is completed and that through 40 and 41 is broken. That is, when the carbons are in 10 contact or the arc is just starting there will be no current flow through either of the lamps, the current flow being solely through the solenoid 37, the wires 38 and 39 and the ballast resistance 36. As soon as the arc has been properly started, 15 however, the circuit through the wires 38 and 39 will be broken and that through 40 and 41 completed, so that all current flowing through the solenoid will now flow through the lamp 35, rather than through the resistance 36, thus 20 converting its energy into useful light. Simultaneously, the switch 34 will complete the circuit through the lamp 31, thus providing a shunt circuit around the solenoid, increasing the total 25 amount of current flow through the arc.

In the particular embodiment of this invention illustrated in Figure 4, the arc through a pair of carbons 51 and 52 is started, as heretofore described, by current flowing through a series circuit including them, the solenoid 53, and the 30 resistance 54. As soon as the arc has been properly started the mercury switch 55 closes, to provide a shunt circuit around the solenoid and resistance 54, which shunt circuit includes in series with the carbons a plurality of auxiliary lamps 56, 35 57, 58 and 59, all of which lamps are wired in parallel. A series of manually operable snap switches 60, 61, 62 and 63 are provided to permit 40 selective operation of one or more of the auxiliary lamps. That is, none of the lamps providing a shunt circuit for additional current flow through the carbons, can come into operation until the circuit is automatically closed by the mercury switch when the carbons have moved to proper 45 operating separation; but once the circuit has been closed by the mercury switch, the manual operation of the snap switches enables the total current through the carbons to be readily adjusted and permits additional current to flow therethrough, not only providing more light as a 50 result of radiations from the arc, but also as a result of radiations from the auxiliary lamps.

Figure 5 illustrates a bank of lamps such as would be used in a blueprint machine, i. e., there are the same number of incandescent lamps 64 or 55 other auxiliary lamps as there are arc lamps 65, and the two types of lamps are mounted alternately in a row.

While I have shown and described certain embodiments of my invention, it is to be understood 60 that it is capable of many modifications. The device to be substituted for the resistance need not necessarily be a lamp but may comprise any other current consuming device or translating device, such, for example, as a motor, which may be 65 used in any kind of service. In some arc lamps now on the market the carbons are pulled apart by a motor driven mechanism and where such arc lamps are used, the resistance of the motor windings may be made use of as a substitute for 70 the incandescent lamp or other auxiliary sources of light. Also, although the switch shown and described in several forms of the invention is preferably a mercury switch, any other suitable type of switch may be used. It may be actuated 75

or controlled electrically or otherwise by the movement of one of the carbons or any of the other movable parts associated therewith. Various changes, therefore, in the construction and arrangement may be made without departing from the spirit and scope of the invention as disclosed in the appended claim, in which it is my intention to claim all novelty inherent in my invention as broadly as permissible, in view of the prior art.

10 The embodiment of the invention shown in Fig. 3 of the drawings is claimed in a divisional application, Serial No. 249,796, filed January 7, 1939.

I claim:

15 Apparatus of the character described, including: an arc lamp comprising a pair of relatively

movable carbons; a solenoid for causing said relative movement; a series circuit including said carbons and said solenoid; a plurality of filament lamps connected in parallel; independent manual switches whereby said filament lamps are selectively controlled; switch means operatively connected to said carbons and affected by movement thereof, said switch being open when said carbons are in contact with each other and closed when said carbons are separated a proper operating distance; and a second series circuit including said carbons, said switch means, and said filament lamps, said second circuit being so arranged that said filament lamps are in shunt about said solenoid.
